FAUCET AND DRINKING FOUNTAIN

Herbert A. Limle, Daytona Beach, Fla.

Application January 2, 1957, Serial No. 632,111

3 Claims. (Cl. 299—10)

This invention is directed to a construction or method for changing a faucet which normally discharges water only downwardly into a combined faucet and drinking fountain which permits the downwardly directed spout of the faucet to be turned upwardly to form a sanitary drinking fountain.

Faucets in large numbers have been sold for use in kitchen sinks and other places, which have fixed, downwardly directed spouts discharging water into the sink or other receptacle for use within the kitchen. To obtain a drink from such a faucet, it has been the practice to fill a glass from the faucet, and then to drink the water out of the glass.

An object of this invention is to provide a construction which permits the previous downwardly directed spout to be moved to a temporary upward direction from which drink water may be obtained in the same manner as from sanitary drinking fountains which have fixed upwardly directed spouts.

Another object of this invention is to permit the downwardly directed spout to be moved forwardly from the base of the faucet, and to be then directed upward for more ready access by the user.

Another object of this invention is to provide intermediate sleeve and inner conduit constructions which may be inserted into the base and spout portions of the original faucet after the spout and base have been cut apart, such constructions being secured therein in such a manner that the spout can be moved to a temporary upward position for drinking purposes.

Another object of this invention is to provide means for the insertion into the base and spout portions of a faucet after such portions have been cut apart, such means providing for locking the spout in the downward position, for releasing the spout for turning the spout to an upward position, and there locking it for temporary use as a drinking fountain.

Further objects of this invention will become apparent as the description proceeds with reference to the accompanying drawings, in which:

Fig. 1 is a side view of a faucet to which this invention has been applied.

Fig. 2 is a portion of Fig. 1 after the spout has been moved forward in preparation for turning it into an upward position.

Fig. 3 is a view similar to Fig. 2 after the spout has been turned to an upward position.

Fig. 4 is a view similar to Fig. 3, after the spout has been moved forwardly a further distance to lock the spout in its upward position.

Figs. 5 and 6 are portions of the spout and pivoted base after the faucet has been cut at 22, Figure 1 to receive the sleeve and conduit portions of this invention.

Figs. 7 and 8 are the front and back intermediate sleeves, shown at 24 and 23 respectively in Figures 10 and 11, which sleeves are to be inserted in the spout and base of the faucet.

Fig. 9 is a cross section of the inner conduit 25 in

Figures 12, 13, and 14 which is to be inserted within the sleeves shown in Figs. 7 and 8.

Figs. 10 through 14 are transverse cross sections taken along the lines 10 through 14 of Fig. 1.

This invention is described in connection with a pivoted kitchen sink faucet, but many of the advantages of this invention are equally applicable to other faucets now on the market or in actual use. This invention is also applicable to original equipment as it is being manufactured.

The faucet includes a pivoted base 20 having a vertical tube portions 20b and a horizontal tube portion 20a, as shown in Figure 1, and a spout 21 which originally were in one integral piece, and were so joined that the spout 21 had a downwardly directed end 21b, and was not upwardly movable. Such a faucet could not be used as a drinking fountain until this invention was applied to it, as shown in the drawings. To apply the invention to the faucet, the horizontal tube portions 20a and the spout 21 were cut along the line 22, Fig. 1, by any suitable instrument. Thereafter the back intermediate sleeve 23 (Fig. 8) the front intermediate sleeve 24 (Fig. 7) and the inner conduit 25 (Fig. 9) are inserted and joined with the tube portion 20a and the horizontal intake 21a of the spout 21 in such a manner that the spout 21 may swing upwardly to discharge water upwardly. The user may then open the well known, and usual valve structure 26, Fig. 1, which is present in every sink of the type herein referred to by means of the well known handle 27 and permit water from the usual cold water supply line 28 to flow through the pipe 29, into the base 20 and into the spout 21. The valve 26, handle 27, cold water pipe 28, pipe 29, pivoted base 20 and hot water pipe 30 have been in use for many years. Their construction and mode of operation are well known, and hence are not further described. If the spout 21 is up, according to this invention, the user can regulate the volume of water by regulating the handle 27 to permit the user to drink without using the usual unsanitary glass 30 normally adjacent the sink. The faucet ordinarily is also connected to the hot water line 30, provided with a similar valve and handle not shown, which are similar to valve 26 and handle 27. Hence the user may also drink hot water, or mixed hot and cold water by proper manipulation of the hot and cold water handles. The valve 26, handle 27, etc., generally are at right angles to the faucet, but are shown in the same plane for better illustration.

Inner conduit 25 has holes 35 through 38 drilled therefor in for the reception of screws shown in Fig. 9. Screw 39 is tightly secured in the hole 35 and then the conduit 25 is inserted from the back into the back intermediate sleeve 23, after which the screws 40 and 41 are tightly secured in the holes 36 and 37. The sleeves 23 and 24 may be formed by cutting a single piece along the plane 22a of Fig. 8, but may be made from separate pieces if desired. The sleeve 23 is cylindrical and has notch 42 cut at the inner end 23a and notches 43 and 44 cut at its outer end 23b. These notches are of a size to receive the round heads of the radially directed members or screws 39, 40 and 41 to lock the spout 21 in the desired downward or upward position, as will become apparent. The conduit 25 has an outer diameter to fit rotatably and snugly within the inner diameter of the sleeves 23 and 24, which have inner diameters substantially equal to the outer diameter of the conduit 25. These sleeves have outer diameters substantially equal to the inner diameters of the pivot base 20 and the spout 21. The sleeve 23 has a hole 48, Figure 8, cut therein which mates with a hole 49a, Figure 6, cut in the base 20. The conduit 25 and the sleeve 23, with screws 39, 40 and 41, are inserted into the base 20, and the screw 49 is inserted and

tightly drawn into the holes 48 and 49a to lock the sleeve 23 in the base 20. The screw 49 is not long enough to contact the conduit 25. The sleeve 24 is inserted within the spout 21 together with the front or forward end 50 of the conduit 25. The sleeve 24 has a hole 51, and the spout 21 has had a hole 52 bored therein, and these holes are aligned with the hole 38 in the conduit 25, after which the screw 53 is inserted and is tightly drawn to lock firmly the conduit 25, sleeve 24 and spout 21 together.

After these parts have been assembled as just described, the faucet structure is ready for use either for filling receptacles in the usual manner there done, or the spout 21 may be turned upwardly and there locked in position for drinking purposes. To move the spout from the downward direction to the upward direction, the spout 21 is first partially pulled forward from the base 20, as shown in Fig. 2. This forward movement removes the heads of the screws 40 and 41 from the slots 43 and 44, and permits the spout 21 to be turned to the upper position shown in Fig. 3. Thereafter the spout 21 is pulled further forward to the position shown in Fig. 4. This causes head of screw 39 to enter the slot 42 and to lock the spout in the upper direction as shown in Fig. 4. The screw 39 prevents the spout 21 and conduit 25 to be completely withdrawn from base 20.

If desired, instead of pulling the spout 21 forwardly as shown in Fig. 4, the user may push the spout 21 toward the base 20, causing the heads of screws 40 and 41 to enter respectively the slots 44 and 43, and thus lock the spout 21 in the upward position.

In operation, if the user desires to fill receptacles in the ordinary manner, the spout 21 is placed, or allowed to remain, in the position shown in Fig. 1, and the valve handle 27 and/or the corresponding hot water handle, not shown, may be turned to operate the corresponding valve structure causing water to enter the base 20 and the spout 21 and be discharged downwardly into the receptacle. When the user desires to obtain a drink, the spout 21 is partially pulled out, as in Fig. 2, turned up to the position shown in Fig. 3, and further pulled out, as shown in Fig. 4, or pushed in, and this locks the spout 21 in the upward position where it may remain as long as desired. When the down position is again desired, the spout is moved to the position shown in Fig. 3, is then turned downwardly to the position shown in Fig. 2, and is pushed in to the position shown in Fig. 1, where it may remain indefinitely until the up position is again desired.

While I have disclosed the preferred embodiment of the invention, as required by the statutes, it is understood that other forms may be used, within the scope of the claims which follow.

I claim:

1. A combined faucet and drinking fountain comprising: a pivoted base having a substantially horizontal tube portion; a faucet spout having a substantially horizontal intake end aligned with and of the same inner diameter as said tube portion and having a discharge end normally downwardly directed; a back sleeve having an outer diameter substantially equal to the inner diameter of said tube portion and snugly fitting in said tube portion and having a notch at its inner end; a screw passing through said tube portion and threadedly engaging said sleeve and locking said sleeve in said tube; an inner conduit having an outer diameter substantially equal to the inner diameter of said back sleeve and snugly and rotatably inserted in said sleeve; a radially directed stop member on said conduit limiting forward movement of said inner conduit within said sleeve and movable to engage said notch when said spout is upwardly directed and pulled out to its outer limit; a front sleeve substan-

tially of the same cross-section as said back sleeve and fitting snugly in said intake end of said faucet spout and receiving the front end of said conduit; a screw passing through said spout, front sleeve and inner conduit and threadedly engaging said front end of said inner conduit and locking said spout, front sleeve and inner conduit together whereby said spout may be moved from a downward position and rotationally locked in an upward position by turning and pulling said spout outwardly.

2. A combined faucet and drinking fountain comprising: a base having a substantially horizontal tube portion; a faucet spout having a substantially horizontal intake end aligned with said tube portion and having a discharge end normally downwardly directed; a back sleeve having an outer diameter substantially equal to the inner diameter of said tube portion and snugly insertable in said tube portion and having diametrically opposed notches at its front end; means for locking said sleeve in said tube portion; an inner conduit having an outer diameter substantially equal to the inner diameter of said back sleeve and snugly and rotatably inserted in said sleeve; means for limiting forward movement of said inner conduit within said sleeve; a radially directed stop member on said inner conduit intake of and adjacent the back end of said spout; a front sleeve in said horizontal intake of said faucet spout receiving the forward end of said inner conduit within said horizontal intake of said spout; a screw passing through said spout, front sleeve, and threadedly engaging said forward end of said inner conduit to lock them together, whereby said faucet spout may be locked in downward and upward positions by pushing said spout backwardly to engage said radially directed stop member in either of said diametrically opposed notches.

3. A combined faucet and drinking fountain comprising: a faucet base having a substantially horizontal tube portion; a faucet spout having a substantially horizontal intake end aligned with and of the same inner diameter as said tube portion and having a discharge end normally downwardly directed; a back sleeve having an outer diameter substantially equal to the inner diameter of said tube portion and snugly fitting in said tube portion; a screw passing through said tube portion and threadedly engaging said sleeve and locking said sleeve in said tube portion; an inner conduit having an outer diameter substantially equal to the inner diameter of said back sleeve and snugly and rotatably inserted and longitudinally movable in said sleeve; a stop member limiting forward movement of said inner conduit within said sleeve when said spout is pulled out to its outer limit; a front sleeve substantially of the same cross-section as said back sleeve and fitting snugly in said intake end of said faucet and receiving the front end of said conduit; a screw passing through said spout, front sleeve and inner conduit and threadedly engaging said front end of said inner conduit and locking said spout, front sleeve and inner conduit together whereby said spout may be moved from a downward position and rotationally placed in a forward and upward position by turning and pulling said spout outwardly.
